US00D571450S

(12) **United States Design Patent** (10) Patent No.: **US D571,450 S**
Brown (45) Date of Patent: **** Jun. 17, 2008**

(54) **DEFLECTING LOUVER WITH DAMPER**

2004/0127154 A1 * 7/2004 Omiya et al. 454/162

(75) Inventor: **Carlton E Brown**, Tucson, AZ (US)

* cited by examiner

(73) Assignee: **AirConcepts, Inc.**, Tucson, AZ (US)

Primary Examiner—Louis S Zarfas

(**) Term: **14 Years**

Assistant Examiner—David G Muller

(21) Appl. No.: **29/299,124**

(74) Attorney, Agent, or Firm—Peter B. Scull; Berenbaum, Weinshienk & Eason

(22) Filed: **Dec. 19, 2007**

(57) **CLAIM**

(51) LOC (8) Cl. 23-04

The design for a deflecting louver with damper, as shown and described.

(52) U.S. Cl. D23/387

DESCRIPTION

(58) **Field of Classification Search** D23/387, D23/373, 370, 371, 393, 391, 324, 385, 386, D23/388, 392, 390; 454/136, 141, 146, 143, 454/153, 162

See application file for complete search history.

FIG. 1 is an isometric view of a deflecting louver with damper;

FIG. 2 is a front side elevational view of the deflecting louver with damper of FIG. 1;

FIG. 3 is a back side elevational view of the deflecting louver with damper of FIG. 1;

FIG. 4 is a top plan view of the deflecting louver with damper of FIG. 1;

FIG. 5 is a bottom plan view of the deflecting louver with damper of FIG. 1;

FIG. 6 is a first side elevational view of the deflecting louver with damper of FIG. 1; and,

FIG. 7 is a second side elevational view of a deflecting louver with damper of FIG. 1.
